(57) CLAIM

The ornamental design for the lamp, as shown and described.

DESCRIPTION

FIG. 1 is a perspective view of a lamp in accordance with the new design;

FIG. 2 is a top view thereof;

FIG. 3 is a front elevational view thereof, a rear elevational view being a mirror image thereof;

FIG. 4 is a side elevational view thereof, an opposing side elevational view being a mirror image thereof; and,

FIG. 5 is a front view of an alternative embodiment of said new design illustrating an upper and a lower portion having indeterminable lengths.

The broken lines in the figures are for illustrative purposes only and form no part of the claimed invention.
